UNITED STATES PATENT OFFICE.

EMIL SCHROEDER, OF NEW YORK, N. Y.

MACHINE FOR GRINDING CUTTERS.

SPECIFICATION forming part of Letters Patent No. 760,926, dated May 24, 1904.

Application filed October 27, 1903. Serial No. 178,694. (No model.)

To all whom it may concern:

Be it known that I, EMIL SCHROEDER, a citizen of the United States, and a resident of the city of New York, (East New York, borough 5 of Brooklyn,) in the county of Kings and State of New York, have invented a new and Improved Machine for Grinding Cutters, of which the following is a full, clear, and exact description.

10 The object of the invention is to provide a new and improved machine more especially designed for accurately grinding rotary cutters—such, for instance, as is used in a fleshing and shaving machine for raw and dressed 15 furs or skins, for which Letters Patent of the United States No. 741,553 has been granted to me on October 13, 1903.

15 The invention consists of novel features and parts and combinations of the same, as will be 20 more fully described hereinafter and then pointed out in the claims.

25 A practical embodiment of the invention is represented in the accompanying drawings, forming a part of this specification, in which similar characters of reference indicate corresponding parts in all the views.

30 Figure 1 is a front elevation of the improvement, parts being in section. Fig. 2 is a side elevation of the same. Fig. 3 is an enlarged 35 sectional plan view of the same. Fig. 4 is an enlarged sectional side elevation of the tool for forming the curry-knife edge on the cutter. Fig. 5 is a cross-section of the cutter after grinding, and Fig. 6 is a similar view 40 of the finished cutter having the curry-knife edge.

45 The cutter A is in the form of a disk secured to a flange A', extending integrally from a pulley A'', having its hub fastened on a spindle A'', hung on centers B B, having handles B' and screwing in bearing-blocks C', attached to the main frame C of the machine. The cutting edge of the cutter A is adapted to be engaged on opposite sides by the peripheral 50 faces of grinding-wheels D D', made of emery or other suitable material and rotating toward each other, as plainly indicated by the arrows in Fig. 1. The grinding-wheels D D' are set one in front of the other, preferably, however, in such a manner that the rear face of

the front grinding-wheel D extends in the same plane as the front face of the rear grinding-wheel D'. (See Fig. 3.) The grinding-wheels D D' are fastened on shafts D² D³, journaled in suitable bearings carried by slides E E', mounted to slide transversely on guideways E², fastened in a slide F, mounted to slide vertically in guideways C², carried on standards C³, forming part of the main frame C. The slides E E' are adjusted transversely by 55 screw-rods E³ E⁴, screwing the slides E and E' and mounted to turn in cross-bars E⁵ E⁶, attached to the outer ends of the guideways E². The screw-rods E³ and E⁴ are provided at their outer ends with handles E⁷ E⁸ under the 60 control of the operator for turning the screw-rods E³ E⁴ to move the slides E and E' transversely on their guideways E², thus shifting the grinding-wheels D and D' correspondingly so as to bring the peripheral edges there- 65 of in proper accurate position relative to the opposite faces of the cutter edge A⁴ of the cutter A. The slide F is adjusted vertically by a screw-rod F', screwing in the slide F and mounted to turn in suitable bearings on the 70 standard C³, and on the upper end of the screw-rod F' is secured a handle F², adapted to be taken hold of by the operator to turn the screw-rod F', so as to raise or lower the slide F and with it the guideways E², slides E and 75 E', and the grinding-wheels D and D', so as to bring the same in proper position in a vertical direction relative to the cutting edge A⁴ of the cutter A to be ground.

80 As shown in the drawings, the top of the cutting edge of the cutter A is slightly below a horizontal plane extending through the axis of the grinding-wheels D and D', so as to obtain the best result.

85 On the shafts D² and D³ of the grinding-wheels D and D' are secured pulleys G and G', around which passes a belt G², also passing over an idler G³, journaled on a bracket G⁴, attached to the slide F, so as to move up and down with the latter to insure the same relation at all times between the idler G³ and the 90 pulleys G and G'. The belt G² passes over a suitable overhead pulley on a counter-shaft, so as to impart a simultaneous rotary motion 95 to the grinding-wheels D and D' in the direc- 100

tion above mentioned, and indicated by the arrows in Fig. 1.

Over the pulley A² of the cutter A passes a belt H, extending downwardly and passing 5 around a pulley H', secured on a shaft I, journaled in suitable bearings in the lower part of the main frame C. On the shaft I are fastened pulleys I' and I², of which the smaller pulley I' is shown connected by a belt I³ with a pulley I⁴ on the main shaft J, likewise journaled 10 on the main frame C and provided with fast and loose pulleys J', connected by a belt with other suitable machinery for imparting a rotary motion to the main shaft J. On the shaft 15 J is also secured a pulley I⁵, adapted to be engaged by the belt I³ at the time it is desired to rotate the shaft I slower, the belt I³ then passing over the larger pulley I². By the arrangement described two different speeds can 20 be given to the cutter A—that is, a high speed is given to the cutter A when grinding the cutting edge A⁴ thereof without taking the temper out of the steel—and when the cutter A is ground and its edge A⁴ is to be turned 25 over to form a curry-knife edge A⁵ (see Fig. 6) then the slow speed is employed—that is, the belt I³ engages the pulleys I⁵ and I².

The tool for turning the edge A⁴ over to form the curry-knife edge A⁵ forms the subject-matter of the divisional application Serial 30 No. 184,558, filed by me December 10, 1903, and this tool is arranged as follows: A friction-roller K is journaled in the forked end K' of a rod K², mounted to slide in a carrier L, and 35 a portion of the rod K² is threaded and engaged by a nut K³, held against longitudinal movement in the carrier L. Now when the nut K³ is turned by the operator the rod K² is caused to slide lengthwise in the carrier L, so as to 40 bring the friction-roller K in proper relation to the edge A⁴ of the cutter A. The carrier L is fulcrumed at its forward end at L' on a base-plate N, fastened by a bolt N' to a swing-plate O, hung on centers P, carried on the main 45 frame C, to allow of swinging the said swing-plate O over into a forward position when the tool is in use (see Fig. 2)—that is, during the grinding operation of the cutter—or to allow of swinging the swing-plate O and the parts 50 carried thereby into an inactive position, as shown in Figs. 3 and 4. The bolt N', previously mentioned, extends through a longitudinal slot O', formed in the swing-plate, to allow of adjusting the base-plate lengthwise 55 on the swing-plate, according to the size of the cutter A under treatment. By the arrangement described it will be seen that the operator in taking hold of the rod K² can impart a swinging motion from the right to the left to 60 the carrier L at the time the friction-roller K engages, say, the right-hand side of the edge A⁴, the friction-roller K at the time standing at an angle to the said edge A⁴. During the swinging motion given to the rod K² by the 65 operator the friction-roller K is caused to

move bodily around and in doing so exerts a gradual pressure on the edge A⁴, so as to turn the same over to form the annular curry-knife edge A⁵. During this operation it is desirable to grease the edge A⁴, as well as the roller K, 70 to insure a gradual and uniform laying over of the cutting edge without danger of injuring the same.

From the foregoing it will be seen that in order to bring the cutter A into a proper condition for fleshing and shaving purposes it is necessary to first grind an accurate circular and sharp cutting edge A⁴ and then turn the said edge over by the tool described, so as to produce the annular curry-knife edge A⁵. 75 When this has been done, the operator turns the crank-handle F² to move the grinding-wheels D and D' upward and then swings the swing-plate O into a backward position, after which the handles B' are turned so as to run 80 the centers B out of engagement with the hub A³ to allow of conveniently removing the cutter A from the grinding and laying-over machine to permit of transferring the cutter to the fleshing and shaving machine. 85

In practice the grinding-wheels are run at the rate of three thousand revolutions a minute to one hundred and fifty revolutions of the cutter during the grinding operation, and for laying or turning the edge A⁴ over the 90 cutter is run about sixteen revolutions per minute. The grinding takes about ten minutes, and the overlaying operation or formation of the annular curry-knife edge usually takes about five minutes; but for either operation it is not necessary to employ highly-skilled labor, as the proper adjustment can 95 readily be made.

Having thus described my invention, I claim as new and desire to secure by Letters Patent — 105

1. In a grinding-machine for grinding circular cutters, the combination with a pair of driven grinding-wheels, arranged one in front of the other, and means for adjusting the grinding-wheels toward and from each other and up and down, of adjustable bearings, and a spindle journaled on the said bearings and carrying a pulley and a flange on which the circular cutter is secured, the said spindle, pulley-flange and cutter forming a unitary 115 structure, removably and adjustably held in the said bearings, to bring the cutter and grinding-wheels in proper relation to each other and to allow of rotating the cutter, as set forth. 120

2. A grinding-machine for grinding circular cutters, comprising a head mounted to slide up and down and provided with transverse guideways, means for adjusting the said head, slides mounted to move in the said guideways, means for moving the slides independently toward and from each other, and grinding-wheels journaled in the said slides, one in front of the other, as set forth. 125

3. A grinding-machine for grinding circu- 130

lar cutters, comprising a head mounted to slide up and down and provided with trans-
verse guideways, means for adjusting the said
head, slides mounted to move in the said guide-
ways, means for moving the slides independ-
ently toward and from each other, grinding-
wheels journaled in the said slides, one in
front of the other, fixed bearing-blocks below
the said grinding-wheels, centers screwing in
the said bearing-blocks, and a spindle hung on

the said centers and provided with a pulley
and flange for carrying the disk to be ground,
as set forth.

In testimony whereof I have signed my name
to this specification in the presence of two sub- 15
scribing witnesses.

EMIL SCHROEDER.
